Aphollos Richmond assignor to
 A. C. Barstow & Co. of Providence R. I.
 Letters Patent No. 301. Dated July 16. 1850.

The Schedule referred to in these Letters Patent and making part of the same.

To all Persons to whom these Presents shall come:

Be it Known, that

I Aphollos Richmond of Providence in the County of Providence and State of Rhode Island have invented or produced a new and useful design, for the top and bottom of a pyramid Stove, and for the door which rests on said bottom, and I do hereby declare that the said new design is fully described & represented in the following specification and accompanying drawings, to which reference is herein after made.

Of the drawings Fig. 1. Plate 1. is a top view or plan of the said top and bottom, placed in the position over each other, they would occupy when set up. In Plate 2, Fig. 2. is an elevation of the bottom, and of the door resting on the same. Fig. 3 is an elevation of the top, and Figs. 4 & 5 are sectional views, showing the mouldings taken in the plane of the line A B Figs. 2 & 3 Plate 2.

The bottom *aaa* of the Stove is cylindroidal in shape, and the top *b b b* is circular, and my new design consists in ornamenting these, and the double doors *c. c.* resting on said bottom, as follows: The outer convex ornamented moulding *d d d* of the bottom has a series of beak-heads *e e e* &c. around it transversely; the next ornamented convex moulding *F F F*, has around it a series of clustered beak-heads, two of which *g g*, are elongated, and arranged longitudinally, the other *h* being arranged transversely between them, all as shown in Fig. 1. Plate 1. and Fig. 2. Plate 2. There is another convex moulding *i i i*, on said bottom, ornamented like that at *d d d*, with transverse beak-heads *k k* &c. as shown in Fig. 2. Plate 2.

The doors *c c.* are ornamented with these beak-heads *l l l* arranged around them, as shown in Fig. 2. Plate 2, and surrounding two sunken gothic arches *m. m.* *m m* arranged side by side, on each door, on the panels of each of which are two beak-heads *n n*; all as shown in Fig. 2. Plate 2.

Dec. 30/

37
The circular top has a convex moulding $o o o$, on its under side, ornamented with transverse beak-heads $p p p$, Fig. 3. Plate 2, and a similar moulding $q q q$, on its upper side similarly ornamented with beak-heads $r r r$ &c. and another convex moulding $s s s$, ornamented with clustered beak-heads $t t t$ arranged as shown in Fig. 1. Plate 1, & Fig. 3. Plate 2, and as described on the moulding $f f f$, of the bottom plate. All the beak-heads herein above referred to, on the several mouldings are cast in alto relief.

Having thus described my new design, I shall state my claim as follows:

What I claim as my invention or production, and desire to have secured to me by Letters Patent, is ornamenting the several mouldings of the top and bottom of a pyramid Stove, and the double door resting on the latter, with transverse, longitudinal and clustered beak-heads, cast in alto relief, as herein above described, and represented in the drawings.

Witnesses.
